UNITED STATES PATENT OFFICE.

ALFRED NORVELL CLOUGH AND CHARLES WILLIAM CLOUGH, OF CHOWCHILLA,
CALIFORNIA.

FOLDING COT.

1,276,033.

Specification of Letters Patent.

Patented Aug. 20, 1918.

Application filed June 20, 1917. Serial No. 175,774.

To all whom it may concern:

Be it known that we, ALFRED NORVELL CLOUGH and CHARLES WILLIAM CLOUGH, citizens of the United States, residing at 5 Chowchilla, in the county of Madera and State of California, have invented new and useful Improvements in Folding Cots, of which the following is a specification.

This invention relates to folding cots; and 10 has for its object to provide a strong and rigid cot capable of being folded and collapsed into a compact bundle suitable for carrying in an automobile or pack.

The distinguishing features of the invention 15 are a rigid frame capable of being folded and collapsed, the use of hinged sections at each end, one of which is adjustable to various angular positions, and the employment of novel and efficient braces and 20 struts to reinforce and support the structure throughout.

One form which our invention may assume is exemplified in the following description and illustrated in the accompanying 25 drawings, in which—

Figure 1 shows a longitudinal, vertical, sectional view of a cot embodying our invention.

Fig. 2 shows an end elevation of the same. 30 Fig. 3 shows an inverted plan view of the frame in folded position.

Fig. 4 shows a similar view of same after it has been collapsed.

In the form shown in the accompanying 35 drawings, we employ a frame made up of intermediate side bars of about one-half the full length of the extended cot, having pivoted at their ends spaced plates 11 carried upon the supporting legs 12. Extension 40 bars 13 are pivotally connected to the plates 11 in line with the bars 10 and transverse bars 14 fit into notches in the outer ends of the bars 13 and are detachable therefrom.

A canvas or other covering 15 is tacked to 45 the intermediate side bars 10 and also to the extension bars 13, being cut away at 16 where the plates 11 occur, and at its ends formed with loops 17 to receive the transverse bars.

The struts or braces for the frame include 50 transverse spacing bars 18 pivoted to each of the legs and formed with a knee joint 19 centrally thereof to permit folding movement upwardly. Diagonal bars 20 are pivotally connected to each leg and an adjacent

spacing bar being also formed with a knee joint to permit upward folding. Between each leg and adjacent intermediate side bar is pivoted a diagonal brace bar 21, knee-jointed to fold upwardly and outwardly, 60 and between each leg and extension bar 13 is a similar jointed bar 22 for supporting the extension frame and knee-jointed to fold upwardly and inwardly.

In the case of one pair of extension bars 65 13, the braces 22 are disconnectable from the legs 12 and are provided with pins 24 to enter apertures at different points in the legs and intermediate frame bars for varying the angular position of the extension 70 frame, whereby a head-rest may be formed for sleeping or a back-rest formed for reclining, as shown in dotted lines in Fig. 1. The ends of the pins 24 are preferably provided with pivoted keepers 25 which are 75 capable of alinement with the pins but are turnable at right angles thereto for locking the pins in the apertures.

In the use of the cot and considering the 80 structure as set up, it is quickly folded and collapsed by removing the transverse end bars 14, folding the extension frames toward the legs and swinging the legs and extension frames into parallel relation with the intermediate frame on the underside 85 thereof, as shown in Fig. 3. The transverse foldable spacing bars 18 are then flexed to permit the side bars to be brought together, as shown in Fig. 4, and the detached end bars 14 are then placed between. 90

The result is a small and compact bundle of about one-half the length of the cot and sufficiently narrow in cross section to be carried easily under the arm. The cot when set up is strong and rigid, being effectively 95 braced and reinforced at all points where strains are likely to occur.

Various changes in the construction and arrangement of the several parts herein shown and described may be employed without departing from the spirit of our invention as disclosed in the appended claim. 100

Having thus described our invention, what we claim and desire to secure by Letters Patent is—

In a folding cot, side members, legs pivoted to the side members to fold there beneath, transverse spacing bars pivoted to the respective legs and each having a knee-joint at its center, and diagonal braces hav- 110

ing knee-joints at their centers connected to the spacing bars and to the legs, all of the knee joints breaking outwardly whereby to allow all of the bars and braces to fold outwardly in the shape of an outwardly pointing **V** with the knee joints of the spacing bars located in spaced relation to the side members and the knee joints of the braces in the spaces between the knee joints of the spacing bars and the respective side members.

In testimony whereof we have hereunto set our hands in the presence of the subscribing witnesses.

ALFRED NORVELL CLOUGH.
CHARLES WILLIAM CLOUGH.
